2 Claims. (Cl. 162—336)

This application is a continuation-in-part of application Serial No. 856,457, filed December 1, 1959, now abandoned.

This invention relates to flow spreader conduits for paper making machines and has as a main object to provide a spreader which will receive the flow from the usual stock supply pipe and spread it smoothly at uniform velocity across the width of the machine to be supplied.

More specifically, the present invention aims to provide an improvement over the type of flow spreader described in the applicant's United States Patent No. 2,465,445, issued March 29, 1949.

As described in this earlier patent, a flow spreader may comprise a single pass which continuously increases symmetrically in width and decreases in depth from its input to its output end, the cross-sectional area of the spreader at its output end being no greater than the cross-sectional area at its input end. In order to increase the squeezing action, whereby the flow is more positively spread throughout the width of the spreader, the cross-sectional area of the spreader conduit may continuously decrease somewhat from its input to its output with consequently increased flow velocity. In other words, the ratio of the cross-sectional area of the inlet end of the spreader may be to the cross-sectional area of its outlet end as one to one, or as one to one minus.

The possible length of a single pass spreader is limited by the space available, and this space is small in the case, for example, of a multi-unit cylinder machine where the spreaders are arranged beneath their associated vats. In such case, the spreader must widen abruptly. Better results are secured where there is a more gradual widening throughout a greater spreading length and in accordance with the earlier invention this greater length is secured in a small space by providing a multiple pass spreader of serpentine or undulatory form with up-passes and down-passes arranged closely together. In this case, as described in United States Patent No. 2,465,445, each of the passes may be of substantially constant cross-sectional area throughout, or the cross-sectional area of each may be continuously decreased somewhat throughout, the turn-arounds at the upper and lower ends of the passes being in one design conveniently of constant width and depth. Even with this arrangement it may be difficult to hold outflow velocity suitably low without the use of an oversize stock inlet connection pipe. This latter difficulty is completely avoided, in accordance with the invention of United States Patent No. 2,465,445, by the use of turn-arounds which enlarge in cross-sectional area in the direction of flow. Using such turn-arounds, each pass can easily have a requisite squeezing action for its spread and the output velocity can be any desired figure.

While the arrangement described in the applicant's United States Patent No. 2,465,445 was a distinct improvement in the art over the existing flow spreaders, it was found that flow spreaders, with the enlarged area of turn-around, gave evidence of insufficient turbulence against the inside radius, and therefore had a tendency of accumulating slime at the beginning of a succeeding pass.

To correct this, in accordance with the present invention, it is proposed to create a turbulence zone at the beginning of each pass by shaping the spreader flow con-

fining walls so that a sudden change of direction is imparted to the flow whereby additional swirls or turbulences occur at each change of direction so that the interior passage is completely filled eliminating slime accumulating areas.

In the case of a single pass spreader, this is accomplished by making the wall facing the inlet as a substantially flat surface disposed at substantially right angles to the incoming flow making the pass fully effective throughout its length.

In the case of multiple pass arrangements, it is proposed that in addition to the turbulence zone created in the first pass that further similar zones are created at each turn-around by reducing the depth of the pass at the point of deflection at each turn-around to substantially less than the depth at the end of the preceding pass. Accordingly, the shape of each turn-around is no longer rounded in the direction of flow but is shaped to produce turbulence and to localize this turbulence in the turn-around passes. In this way, each succeeding pass becomes effective throughout substantially its entire length eliminating the slime accumulating tendencies mentioned above.

Having thus generally described the nature of the invention, particular reference will be made to the accompanying drawings showing by way of illustration a preferred embodiment thereof, and in which:

FIGURE 1 is an elevation of a cylinder machine installation with stock feeding means including a spreader having multiple passes with turn-arounds wherein at each end of direction diverting baffle the depth of the pass is reduced relative to the depth at the end of the preceding pass, thus producing a localized turbulence.

FIGURE 2 is an enlarged side elevation of the spreader utilized in the construction of FIGURE 1.

FIGURE 3 is an enlarged end elevation of the spreader of FIGURE 2.

FIGURE 4 is an enlarged side elevation of a single pass flow spreader suitable for embodiment with construction shown in FIGURE 1.

FIGURE 5 is an enlarged sectional view of the lower end of the construction shown in FIGURE 4 to illustrate the turbulizing action of the substantially flat back wall abruptly changing direction of flow from the inlet.

In FIGURE 1, reference numeral 11 designates a cylinder machine including a vat 12 and a cylinder 13, the latter being driven by a motor 14. Reference numeral 15 designates generally a spreader in accordance with the invention disposed below the machine 11 and in connection with the vat inlet opening by means of a conduit section 16. Reference numeral 17 designates a white water conduit in connection with the vat and leading to a mixer 18 to which is also led the circulating stock outlet 19 from the vat and an input pipe 20 for new stock. The mixture is forced by a pump, not shown, into the lower end of a head box comprising an upwardly opened conical tank 21 concentrically disposed within an upwardly open conical tank 22. The mixture pumped into the tank 21 flows evenly over the top dam 24 with air removal, into the annular space between the two tanks. The stock flows from the bottom of tank 22 through a pipe 26, which is inclined somewhat upwardly in the direction of flow, to a downpipe 27 in connection with a fitting 28 which, as shown in FIGURE 2, is made as an integral part of the construction of the first pass 31 and has a circular section extending to and abutting a back plate 34.

The lower end of the side walls of the first pass 31 is conformed to match the contours of the fitting 28 at each side with the front plate 35 intersecting and meeting the upper contour of the fitting. Accordingly, and as will be described in more detail later, the input or inlet end 29 of the fitting is circular and the formation of the section

of the first pass 31 at the point of intersection with the fitting 28 will be rectangular. This, of course, would also apply to the inlet end 129 and the formation of the section of the single pass construction 131, as shown in FIGURES 4 and 5. The substantially right-angled intersection of the fitting 128 with the beginning of the single pass 131 produces a sudden change of direction to the flow, as shown somewhat diagrammatically in FIGURE 5 creating a zone of small turbulences and thus breaks down the flow so that it fills the entire passage making the pass fully effective throughout its length. This feature of the single pass spreader is, of course, inherent in the first pass 31 of the multi-pass spreader as will be described.

Dealing now with the multi-pass construction shown, and by way of illustration, it will be assumed that the feed conduit 26, 27 is of 24 inch nominal diameter and that the machine 11 has a vat width of 140 inches.

The inlet opening 29 of fitting 28 has a diameter of 23 $\frac{5}{8}$ " and the rectangular pass section or outlet 30, located along a line parallel with the top of the fitting 28, has a width of 23 $\frac{5}{8}$ " and a depth of 18 $\frac{1}{2}$ ". This gives an input area of 438 sq. in. and a substantially equal output area, i.e. 437 sq. in. at the inlet opening or start of the first pass.

As previously mentioned, it will be noted that the substantially right-angled interconnection of the fitting 28 with the first pass 31 produces a turbulentizing effect to the flow of stock delivered to the first pass and thus eliminates possible cavitation at this point making the first pass fully effective throughout its length.

The first pass 31 of the spreader is disposed vertically on fitting 28 and is 5' 7" in height and has a rectangular horizontal outlet opening which is 54" in width and 7" in depth and is symmetrically disposed with respect to the inlet opening, i.e. the side walls of the pass diverge at equal angles from the vertical. The cross-sectional area of the pass is reduced at the rate of 2 $\frac{1}{2}$ % per running foot or for a total of about 14%. The area of the outlet opening is 378 sq. in. which is a reduction of 59 sq. in.

If two rectangles of different size in parallel planes are connected by straight lines joining their corners, then the rectangles of intermediate parallel planes will not bear a relation to the area of the end rectangles proportional to their distances from them in accordance with the present requirements. For example, the mid-area, or area of the rectangle parallel to and equidistant from the other two planes, will not be equal to the average of the other two areas, but much greater. Therefore, if the pass 31 were defined by four straight plates, the area between the inlet and outlet would actually be considerably greater through most of the length of the pass than the area at the inlet. There would not be a constant rate of change in area and squeezing action for every foot of the spreading length. The pass 31, with the input and output dimensions above given, would have an intermediate area of 497 sq. in., an error of about 21%. In order to avoid this discrepancy and this should be done for the best results, the side plates 32 and 33 down to the connection with the fitting 28 and the back plate 34 of pass 31 may be flat, the front plate 35 being shaped as particularly shown in FIGURE 2 so that the cross-sectional area of the passage is reduced at a constant rate. The front plate 35 is inwardly bowed giving a depth at one foot intervals, moving up, of 14.7", 12", 10.1", 8.7" and 7.5".

Reference numeral 36 designates a turn-around having an inverted U-shaped passage 37. One leg of the turn-around is secured to the upper end of pass 31 and has an opening of the same dimensions as the outlet opening of the latter. As here shown, the passage 37 has a constant width but enlarges in depth to a rectangular outlet opening whose depth is 12.31" with an area of 665 sq. in. The turn-around has a mean flow length of 2 $\frac{1}{8}$ ". The output leg of the turn-around 36 is secured to the top of a

pass 38 having a passage defined by straight side plates 39 and 40 and a straight back plate 41, the front plate 42 being bowed inwardly to obtain the constant effect above mentioned.

In accordance with the present invention, the top or baffle portion 36a of the turn-around is made as being substantially flat rather than a rounded section as shown in the applicant's earlier United States Patent 2,465,445. This change in formation reduces the depth of the passage 37 at the point "A" to substantially less than the depth of the pass 31 at the upper end. For example, as noted above, if the depth of the outlet end of the pass 31 is 7" the depth of the passage 37 is approximately 3 $\frac{1}{2}$ " at point "A" while the width remains constant. This creates a turbulence chamber or zone "B" producing a localized scouring action eliminating the possibilities of slime accumulation at the beginning of the succeeding pass 38. Further, this localized turbulence at the turn-around by eliminating possible cavitation extends the effective length of the succeeding spreader pass 38.

Pass 38 has an upper or inlet opening of the same dimensions as the outlet opening of the turn-around and has a bottom rectangular opening which is 93" in width and 5.75" in depth, providing an outlet opening of 535 sq. in. This is a reduction of 130 sq. in., or about 19%, from the inlet. This pass is 77" in length and, moving downwardly at one foot intervals, its depth is 10.9", 9.8", 8.85", 8", 7.25", 6.62" and 6.05".

Reference numeral 43 designates a bottom turn-around having a U-shaped passage 44 with an inlet communicating with and having the same dimensions as the outlet of pass 38. Turn-around 43 is of constant width but increases in depth to an outlet opening whose depth is 10.25" with an area of 953 sq. in. The mean flow length is 1' 10 $\frac{1}{4}$ ".

Again, the bottom or baffle portion 43a of the turn-around is made as being substantially flat so as to reduce the depth of the passage 44 at point "C" to substantially less than the depth of the pass 38. For example, as noted above, if the pass 38 has a depth at the outlet opening of 5.75", the depth of the passage 44 is approximately 2.875" at point "C" while the width remains constant.

In each case the turn-arounds will be of a flattened conformation at the point of redirection of the flow with the flow passage being reduced in depth substantially midway of the turn-around so as to be of considerably lesser depth than the depth of the outlet end of the preceding pass while maintaining a constant width. By way of an example, the depth of the turn-around flow passage at mid-point is preferably approximately half the depth of the outlet opening of the preceding path while the width of the turn-around remains constant. This produces a localized zone of turbulence within the turn-around pass making each succeeding pass effective throughout substantially its whole length.

As previously discussed, the construction of the fitting 28 and the connection to the inlet end of the first pass 31 also produces a zone of turbulence at this point making the first pass effective throughout substantially its entire length.

Reference numeral 45 designates a pass having an inlet opening of the same dimensions as the outlet end of turn-around 43 and in communication therewith. The pass is defined by straight side plates 46 and 47 and a straight back plate 48, the front plate 49 being bowed inwardly and the arrangement being such as to provide an outlet opening having a width of 140" and a depth of 5 $\frac{1}{4}$ ", giving an area of 735 sq. in. The reduction in the area is 217 sq. in. or about 22.7%. The pass 45 is 9'1" high and, moving up at one foot intervals, the shape of the front plate 49 is such that the depths are as follows: 9.45", 8.75", 8.1", 7.5", 7", 6.5", 5.6" and 5.28".

The top of the pass 45 is connected directly with the feed opening 70 of the vat 12 as shown in FIGURE 1.

It has been assumed in the above description that the vat width is 140", but the vat width could be anywhere

from that figure down to 93". In the latter case, keeping the same depth at the outlet end of the final pass, the outlet area would be 488 sq. in., a decrease in area of 465 sq. in. With a 140" spreader and a velocity of 5.9 f.p.s. at fitting 28 the velocity will rise to 6.8 at the top of the first pass, drop to 3.9 in the top turn-around, rise to 4.8 in the second or down-pass, drop to 2.7 in the bottom turn-around, and rise in the final pass to 3.5 at 8,000 g.p.m. In the 93" spreader, with an input velocity of 3.9 f.p.s., the velocity will rise to 4.5 in the first pass, drop to 2.6 in the top turn-around, rise to 3.2 in the down-pass, drop to 1.8 in the bottom turn-around, and rise to 3.5 at the top of the final up-pass at an output of 5,300 g.p.m.

The over-all length of the illustrated multi-pass spreader, with fitting 28, is less than 6 feet so that it is readily disposable beneath an associated vat which will have, for example, a length in the neighbourhood of 9 feet.

Using a rated 20" inlet fitting, the final spread can be from 79" to 120" in width with a depth of 4.25"; with a 30" diameter inlet fitting the outlet opening can have a width of from 119" to 180" with a depth of 6½"; and with a 38" diameter inlet fitting the outlet opening can be from 157" to 240" in width with a depth of 7¾". Thus with the four sizes of inlets i.e. 20", 24", 30" and 38", the spread can range anywhere from 79" to 240".

Fitting 28 is provided with bottom clean-out doors 50 at each side, see FIGURE 3. The up-pass 31 has wash-out doors 52 and 53 near its upper end and the turn-around 36 has wash-out doors 54 and 55. The top wall of the turn-around is provided with an outlet nipple 57. A pipe 58 connects nipple 57 with the white water pipe 17. A pipe 62 connects the highest part of the inclined stock feed pipe 26 with white water pipe 17, thus preventing the formation of air locks and air venting to the feed system in advance of the air release means constituted by the up-flow head box. The venting system must always be on the rise or at least must not dip below horizontal since otherwise an air lock will form in it.

In FIGURE 3 it will be seen that the down-pass 38 and the final up-pass 45 are provided near their upper ends with wash-out doors and that the bottom turn-around 43 is provided at one side with a wash-out door 65 and at the other with a dump valve 66.

In FIGURES 1, 2 and 3, three spreading passes are shown but any appropriate number from two on up may be used. With reference to FIGURE 4, a single pass spreader, in accordance with the invention, can be varied in length to suit requirements with the top 145 of the

pass being adapted for connection directly to the feed opening 70 of the vat 12, as shown in FIGURE 1.

I claim:

- 5 1. In a flow spreader conduit for a paper making machine, said conduit having an inlet opening for connection to a stock supply pipe, said conduit having an outlet opening whose width is substantially that of the machine, said conduit being of undulatory form and comprising at least two generally upright serially connected passes each having an inlet and outlet end, and a turn-around connecting adjacent ends, the outlet end of one with the inlet end of the following of said passes, each of said passes progressively increasing in width and decreasing in depth in the direction of flow, the cross-sectional area 10 of the outlet end of each pass being no greater than that of its inlet end, said turn-around having a reduction in depth intermediate said input and output end to substantially less than the depth at the end of the preceding pass; the improvement wherein said turn-around has a flat outer flow confining wall at right angles to the mean direction of flow in said passes spanning said passes and the point of said reduction in depth whereby a localized turbulence is created within said turn-around larger area output end.
- 15 2. A flow spreader as claimed in claim 1, wherein the depth of turn-around at said point of reduction is substantially half the depth of the outlet end of an upright pass and the width of said turn-around remains constant between said inlet and outlet ends.
